UNITED STATES PATENT OFFICE.

GEORGE W. MORRISON, OF LEWISTON, IDAHO.

COMBINED DESK AND CHAIR.

1,288,119.

Specification of Letters Patent. Patented Dec. 17, 1918.

Application filed September 6, 1916. Serial No. 118,769.

To all whom it may concern:

Be it known that I, GEORGE W. MORRISON, a citizen of the United States, residing at Lewiston, in the county of Nez Perce 5 and State of Idaho, have invented a new and useful Combined Desk and Chair, of which the following is a specification.

The invention relates to combined desks and chairs, and more especially to that class 10 used in schools, or the like, and wherein the desk and chair are connected to form a unit, with the desk for one student attached to and in rear of the seat for another student.

An object is to simplify the construction 15 and reduce the cost of manufacture of such desks, and is particularly designed to improve the structure disclosed in Letters Patent No. 1,200,693, granted to E. H. Barton and myself October 10, 1916, by eliminating therefrom the additional casting comprising the rear legs of the tripod for 20 separately supporting the adjustable seat, and to provide means for the rigid attachment of a single supporting member to the 25 front face of the next succeeding desk support in such a manner as to permit of its ready application thereto or detachment therefrom for the purpose of storage or shipment.

Another object is to provide a desk and 30 chair support which occupies a minimum amount of floor space, thus avoiding, as much as possible, corners or places for dust and dirt to accumulate, and which will, consequently, permit of readily washing, sweeping, 35 or otherwise treating the floor.

A full and complete understanding of 40 the invention may be obtained from a consideration of the following detailed description, taken in connection with the accompanying drawings forming part of this specification; it being understood that while the drawings show a practical form of the invention, the latter is not confined to strict 45 conformity therewith, but may be changed or modified, as long as such changes or modifications mark no material departure from the salient features of the invention, as specifically pointed out in the claims hereto 50 appended.

In the drawings in which like reference characters designate like parts in each of the several figures:—

Figure 1 is a side elevation of a combined 55 desk and chair support, constructed in accordance with this invention.

Fig. 2 is an enlarged detail sectional view on the line 2—2 of Fig. 1.

Fig. 3 is a similar view on the line 3—3 of Fig. 1. 60

Fig. 4 is a similar view on the line 4—4 of Fig. 3.

Fig. 5 is a rear elevation of the desk and chair support, as shown in Fig. 1.

Fig. 6 is a detail horizontal sectional view, 65 on the line 6—6 of Fig. 5.

In the drawings, 1 represents a desk support having adjustable desk supporting means 2 located at the top thereof and supporting a desk 3 of the construction ordinarily used in schools, or the like, all of which is substantially the same as illustrated in the said Letters Patent. The desk supporting means 1 comprises an arched member composed of two spaced, bowed legs 4, 70 having integral flared feet 5 formed at their lowermost extremities to rest upon and be secured to the floor in the ordinary manner. This arch is preferably of flanged construction to lend additional strength and rigidity 75 thereto. 80

A centrally located upstanding desk supporting post 6 is arranged at the apex of the arch and is preferably formed integral therewith, and having the rearwardly extending vertically disposed marginal flanges 7 for a purpose to be hereinafter described. 85 A vertically disposed slot 8 is formed in the post 6 and extends from an intermediate point thereof to a point adjacent the top extremity of said post 6 and is adapted to receive a screw 9, or other binding means which passes therethrough and enters the aforesaid desk supporting bracket 2, and is adapted to support the said desk at any desired elevation within the limits of the said slot 8, the bracket 2 being guided in its upward and downward adjustment between the marginal flanges 7. The book supporting shelf 11 of the desk is preferably provided 90 with an aperture 12 for the purpose of receiving the upper end of the post 6 within the confines of the said desk. 100

The desk supporting post 6 is further provided on the face opposite to the marginal flanges 7 with relatively short spaced ribs 13 vertically arranged and in parallel relation to each other. These ribs 13 rise from the crown of the arch 1 and have their opposed faces 14 tapered and are adapted to 105 form a guide way for and prevent lateral displacement of a seat supporting member 110

15 to be described. Between the ribs 13, there is provided a horizontally disposed lug or projection 16 extending outwardly from the face of the post 6 a distance approximately one half the depth of the ribs 13, said projection being provided with a bolt opening 17 formed centrally of the projection 16 and coinciding with a counter-sink 18 formed in that side of the post 6 opposite to the ribs 13 and arranged midway between the flanges 7. A shoulder 19 is provided at the top of the arch 1 at the point of intersection thereof with the post 6.

The seat supporting member 15 is composed of a suitably flanged bar or casting having the bent upper and lower terminal portions 20 and 21 adapted to fit against the front face of the desk supporting post 6 and the floor respectively. The seat supporting member 15 is thus located in an inclined position, the lower end 21 thereof rising substantially vertically from the floor and adapted to be made fast thereto by screws, or the like, the upper end 20 resting in a horizontal position against the front face of the post 6 and between the ribs 13, the vertical side edges of said horizontal portion 20 being tapered to fit between the said ribs. An opening 22 is provided in the web of the horizontal portion 20 of the seat supporting member 15, adjacent to the end thereof to provide an end wall 23 extending the full width of the flanges of the said member 15, which flanges are flared or widened, as indicated at 24 along the horizontal portion 20, to lend additional strength thereto, and compensate for the opening.

A recess or groove 25 corresponding in shape and size to the lug or projection 16 is provided on the vertical terminal wall of the member 15 and is adapted to receive the same when the parts are in applied position, and to lie between the ribs 13 and to rest upon the aforesaid shoulder 19 at the lower edge thereof. A centrally located bolt opening 26 is provided in the end wall of the member 15 in registering relation to the bolt opening 17, and is adapted to receive therethrough the bolt 27, the head 28 of which lies in the counter-sink 18 and is prevented from turning thereby, and a nut 29 is applied to the threaded end of the bolt 27 within the opening 22, which opening permits of the ready application and adjustment of the nut 29, when assembling the parts.

The seat supporting member 15 is provided with means for adjustably mounting the seat 30 thereon, to permit of the upward or downward and consequent rearward or forward movement of the seat to adapt the same to different size occupants, but since this means is shown, described and claimed in the aforementioned Letters Patent, it is not deemed necessary to describe the same

herein in detail and no claim is made thereto. It will be seen from the foregoing that the structure as disclosed in said Letters Patent has been greatly simplified and the cost of production reduced to a minimum, since the heavy casting comprising the rear legs of the seat supporting tripod, as disclosed therein, has been eliminated, and a single bar or member 15 is used for supporting the seat, resulting in an economy of parts and having a minimum number of points of attachment to the floor, which is a great advantage as it facilitates sweeping or otherwise treating the same.

The attachment of the member 15 to the desk supporting member 1 may be readily accomplished by the simple manipulation of a single bolt when the parts are rigidly secured together and the accidental displacement thereof is prevented.

What is claimed is:—

1. In a combined desk and chair, a desk support consisting of an arch forming a pair of bowed legs adapted to rest upon the floor, and a centrally located vertically disposed post extending upwardly from the crown of the arch and integral therewith, a desk supporting bracket, adjustable means for connecting the bracket to the post to provide for the adjustment of the desk, an inclined seat supporting member adapted to rest upon the floor and forming with the bowed legs a tripod support, means for adjusting the chair along said member, and interlocking and securing means between the upper end of said member and the face of the post for detachably securing said parts together at the point where the post rises from the arch.

2. In a combined desk and chair, a desk post, a desk supporting bracket slidably mounted upon said post, means for adjusting said bracket upon said post, a seat at the lower end of the post comprising a horizontally disposed projection formed on the face of the post opposite to that upon which the bracket slides, a bolt hole extending through said projection and post and provided with a counter-sink therein, a seat supporting member engaging said seat and projection, and a bolt extending through said hole and having a head in said counter-sink for connecting the seat supporting member to said post and to allow the vertical adjustment of said desk bracket without interference.

3. In a combined desk and chair support, a desk-supporting post, an outstanding horizontally disposed projection formed on the post and having a bolt hole, a horizontal shoulder formed on the post below the projection, vertically disposed spaced ribs provided on the post at each side of the projection, said ribs rising from the shoulder and in spaced relation to the bolt hole, an out-

wardly and downwardly extending seat supporting member having its upper end fitted between the said ribs, resting on said shoulder and provided with a horizontally disposed recess to receive and interlock with said projection, said member having a transverse opening spaced from the upper end thereof, leaving an end wall in which the said recess is formed, said end wall having 5 a bolt hole in registering relation with the bolt hole of the said projection, and a bolt passed through said holes and provided with a nut exposed at the transverse opening.

4. In a combined desk and chair support, 10 the combination with an upstanding desk supporting post provided at its base with a horizontal shoulder, spaced ribs rising on one face of the post from the said shoulder and having tapered opposing faces, a horizontally disposed projection formed on the face of the post between the ribs and in spaced relation to the shoulder, said projection having a bolt opening traversing its

center, a counter-sink formed on the opposite face of the post and registering with the bolt opening, an inclined seat supporting member resting on said shoulder, having a horizontally disposed upper end, and provided with a transverse opening formed near said end, the vertical side edges of said end 25 being tapered and adapted to fit against the desk supporting post and between the ribs, said end also having a horizontally disposed recess to receive the projection on the post, and a bolt opening traversing the end and 30 registering with the bolt hole in the post, and a bolt adapted to register with the openings and to bind the parts together.

In testimony, that I claim the foregoing 35 as my own, I have hereto affixed my signature in the presence of two witnesses.

GEORGE W. MORRISON.
